UNITED STATES PATENT OFFICE.

EMILE MASSIS, OF LONDON, ENGLAND.

BALANCED WINDOW-SASH.

1,347,703.

Specification for Design.

Patented July 27, 1920.

Application filed July 16, 1919. Serial No. 311,291.

To all whom it may concern:

Be it known that I, EMILE MASSIS, a citizen of the French Republic, residing at London, England, have invented certain 5 new and useful Improvements in Balanced Window-Sashes, of which the following is a specification.

This invention relates to balanced window sashes for railroad cars, street cars, 10 automobiles and other vehicles.

The principal object of the invention is to afford means for raising and lowering the window with a minimum of exertion and for retaining the window in either the open 15 or the closed position, or in an intermediate partly-raised position.

A further object is to provide improved means for balancing the weight of the window sash by means of a lazy tongs device, 20 assisted by springs which may be made to balance as large a proportion of the weight as desired or to overbalance the weight and therefore normally to close the window.

Other objects of the invention are to enable 25 the balancing springs to work under favorable conditions by mounting them on guide rods or tubes so as to prevent distortion, and to enable lubricant to be retained for the sliding surfaces.

The invention is designed for application 30 to existing constructions, all the necessary working parts being accommodated in the usual well or opening into which the window sash descends, with an operating device 35 vice projecting to within reach of the occupants of the vehicle.

Referring to the accompanying drawings, Figure 1 is a front elevation showing a carriage door fitted with the present invention, 40 the inside panel of the door being removed.

Fig. 2 is a side elevation in section, showing a double or auxiliary lazy tongs.

Fig. 3 shows an alternative form of handle for raising the window and Fig. 4 45 shows another arrangement employing a strap.

Fig. 5 is a detail showing the use of tension springs applied to the lazy tongs.

Fig. 6 shows compression springs incased 50 in tubes.

According to the present invention, a set of lazy tongs levers is pivotally secured at bottom to a bracket inside the well or opening into which the window sash descends 55 and at top to sliders arranged to travel upon a cross rod or within tubes attached

to the window sash. These sliders are pivoted to the tops of the lazy tongs and as they move outwardly extend or compress springs which tend to force inwardly the 60 sliders and the tops of the lazy tongs, and thereby to balance the weight of the window-sash.

The set of lazy tongs *a a* is pivoted at bottom to bracket *b* and at top to sliders *c c'* designed to travel on cross rod *d*, Figs. 1 and 2. The sliders *c c'* are pivoted to the tops of the members of the lazy tongs *a a* and are constantly pressed inwardly by springs *e*. The connection of the lazy tongs *a a* with the pivot *b'* of bracket *b* is effected through links *f f* which are pivoted to and project inwardly from the bottom members *a a*. The auxiliary lazy tongs *h h* are also mounted on the pivot *b'* and their lower links *g g* move always parallel with the bottom members *f f*. The pivots *i* serving for both sets of lazy tongs *a f* and *g h* are coaxial. The connecting rod *j* is secured to the top of the auxiliary lazy tongs *h h* and by means of this rod *j* the window *k* carried by the cross rod *d* can be raised or lowered. By moving this rod *j* up or down, the auxiliary lazy tongs *h h* will be extended or closed up and at the same time the lazy 70 tongs *a a* which supports the window, will be raised or lowered. If desired, the auxiliary lazy tongs may be suppressed, and the operating rod *j* secured direct to the pivot of the main levers *a a*, as seen in 75 Fig. 1.

Any suitable form of handle may be employed to operate the rod *j*. In Figs. 1 and 2 I have shown a crank handle *l* pivoted in a plate upon the door and provided with a pinion *m* meshing with a rack *n* secured to rod *j*. The rod *j* travels through a guide *j'* and the rack is supported by a roller *m'* on the side opposite to the pinion *m*. By turning the crank *l* the rod *j* will be depressed or raised and the window can then be locked if required by any suitable catch or other means. In Fig. 3, I have shown an alternative form of handle. The rod *j* is cranked at *j'* to pass through the inside 80 panel of the door. A spring *p* normally presses outwardly a handle *q* which can slide on the part *j'* and this handle is fitted with a neck *q'* which at its extremity carries a transverse pin *r* resting on top of the cranked portion *j'*. The door panel is slotted as at *s* to allow the handle *q* and 85

part j' to slide in the panel so that the pin r can engage under serrations t in a pair of plates arranged one at each side of the slot s : the serrations may be arranged as shown 5 to hold the sash down, when the weight is overbalanced by the springs. The dotted lines in Fig. 3 show other positions of the handle q and cranked part j' .

In Fig. 4, the window sash is provided 10 with a strap u passing over a roller u' on the upper edge of the inner panel of the door, so as to be operated and secured within the carriage in the usual manner. The supporting springs may be arranged to balance 15 only a portion of the weight of the window and to allow the latter to fall when the strap is released, but I prefer to balance the entire weight and to arrange for the sash to be pulled down by hand to open the 20 window.

Instead of employing springs in compression, the springs may be arranged to act in tension, and they may be located at other suitable points than the position shown in 25 Figs. 1 and 2. For example, Fig. 5 illustrates a tension spring e' connecting the pivots of the lazy tongs and thereby exerting a balancing pressure to support the sash.

Fig. 6 shows the use of compression 30 springs e , which instead of being threaded on the guide rods d as in Figs. 1 and 2, are incased in slotted tubes v , within which the dies or sliders c c' travel. Pivot pins e^2 project from the sliders through the lateral slots v' and engage the upper ends of 35 the lazy tongs as in the previous construction. The tubes may be filled with grease to lubricate the sliding parts.

What I claim is:—

40 1. A balanced window sash, comprising a lazy tongs device, a fixed pivot for the lower end of said lazy tongs, sliders connected to the upper extremities of said lazy tongs, a guide tube secured to the bottom of said sash, said sliders reciprocable in said guide tube, and springs inclosed in said tube acting upon said sliders.

45 2. A balanced window sash, comprising a lazy tongs device, a fixed pivot for the lower end of said lazy tongs, a guide tube secured

to the bottom of said sash, said guide tube slotted longitudinally, sliders reciprocable in said slotted guide tube, springs inclosed in said slotted tube acting upon said sliders, and means for connecting said sliders to the upper extremities of said lazy tongs, said connecting means extending through the slotted portion of said guide tube. 55

3. A balanced window sash for vehicles, comprising a lazy-tongs device, a guide secured to the bottom of the sash, sliders reciprocable along said guide, said sliders connected to the upper extremities of said lazy-tongs, a fixed pivot for the lower extremities of said lazy-tongs, and springs acting 60 upon said sliders, said springs being coaxial with said guide. 65

4. A balanced window sash, comprising a lazy tongs device, a guide secured to the bottom of the sash, sliders reciprocable 70 along said guide, said sliders connected to the upper extremities of said lazy tongs, a fixed pivot for the lower extremities of said lazy tongs, springs acting upon said sliders to extend said lazy tongs, said springs being 75 coaxial with said guide, a control rod connected to said lazy tongs device, a rack upon said control rod, a pinion meshing with said rack, a roller supporting said rack in mesh with said pinion, and means for rotating 80 said pinion to raise or lower the sash.

5. A balanced window sash, comprising a lazy tongs device, a fixed pivot for the lower end of said lazy tongs, a guide tube secured to the bottom of said sash, said guide tube 85 slotted longitudinally, sliders reciprocable in said slotted guide tube, springs inclosed in said guide tube acting upon said sliders, said sliders being connected to the upper ends of said lazy tongs and said springs 90 tending to extend said lazy tongs, a control rod connected to said lazy tongs device, and means for operating said control rod.

In testimony whereof I affix my signature in presence of two witnesses.

EMILE MASSIS.
